UNITED STATES PATENT OFFICE.

ROBERT KESSLER, OF SCRANTON, PENNSYLVANIA.

VENDING MACHINE.

Application filed April 29, 1926. Serial No. 105,547.

My invention relates to vending machines and has for its object the provision of a machine from which a plurality of articles or packages may be selectively dispensed. The invention seeks to provide a mechanism in which a plurality of articles or packages may be viewed by a purchaser and a selected package or article brought into position to be withdrawn from the machine by the customer. The invention also has for its object the provision of means whereby the withdrawal of the article or package will be prevented until the proper coins have been deposited, and another object of the invention is to provide novel means whereby after the deposit of the coins the package or article will be rendered accessible. These stated objects, and other objects which will incidentally appear in the course of the following description, are attained in such a mechanism as is illustrated in the accompanying drawings, and the invention resides in certain novel features which will be particularly pointed out in the appended claims.

In the drawings:

Figure 1 is a plan view, partly broken away, of a machine embodying my invention;

Fig. 2 is a front elevation of the same;

Fig. 3 is an enlarged vertical section on the line 3—3 of Fig. 2;

Fig. 4 is an enlarged vertical section on the line 4—4 of Fig. 2;

Fig. 5 is a sectional elevation on the line 5—5 of Fig. 4;

Fig. 6 is a horizontal section on the line 6—6 of Fig. 5;

Fig. 7 is a detail showing a corner of the door;

Fig. 8 is a bottom plan view of a portion of the turntable or package carrier.

The casing 1 may be of any preferred form or dimensions and may be constructed with one compartment or a plurality of compartments each containing a mechanism embodying the invention so that within a limited space a large variety of merchandise may be displayed and vended. The top of the frame or cabinet is covered by a pane of glass or other transparent material 2, and, if desired, the sides of the cabinet may be made of the same material so that the merchandise displayed for sale may be readily viewed by a prospective customer. The merchandise is arranged upon a turntable or tray 3 upon which are secured a plurality of radial par-

titions 4 whereby a plurality of compartments is produced, and this tray is provided at its center on its under side with a pivot post or stud 5 adapted to seat within a bearing 6 upon a supporting frame 7 which is engaged upon cleats or other supports 8 within the frame or cabinet so that an empty tray may be readily withdrawn and a filled tray substituted therefor. It will be understood that the back of the cabinet or enclosing frame is provided with a removable wall or a door which is normally locked, so that the insertion and removal of the trays will be easily accomplished. The tray is provided on its under side with a circular gear rack 9 meshing with a pinion 10 on the inner end of a shaft 11 which is journaled in suitable bearings provided therefor in the front wall of the cabinet or frame and equipped at its outer end with a turning knob or handle 12, as shown: When a purchaser desires to obtain some article or package displayed upon the tray, he rotates the shaft 11 through manipulation of the knob 12 in an obvious manner so that the tray is rotated about the center 5 until the compartment containing the desired article or package is brought into the delivery position. In order that the tray may move easily, rollers 13 are provided upon the supporting frame 7, as shown in Fig. 3, and the tray rests upon these rollers so that it will move easily and will be supported in a horizontal position at all times. Within the cabinet at the front side of the same is a hood 14 of proper form and dimensions to extend over and enclose the particular compartment on the tray from which the goods are to be removed, and this hood communicates directly with the opening 15 in the front wall of the casing, which opening is normally closed by a door 16.

In the illustrated embodiment of the invention, the door 16 is mounted for sliding movement in channels or tracks 17 provided therefor at the top and bottom of the door opening and is normally held against movement by a bolt 18 mounted vertically in suitable guides provided therefor below and at one side of the door opening and pivotally attached at its lower end to a lever or trigger arm 19 which is pivoted between its ends upon a bracket or supporting frame 20 secured within the cabinet adjacent the door opening. The inner end of this lever or trigger arm 19 extends upwardly and is

equipped with a roller 21 which bears against the under side of the carrier or tray 3 and is adapted to engage or seat in any one of a series of recesses 22, provided in the bottom of the tray, as the compartments thereon are brought under the hood 14. A spring 23 is attached to the front portion of the arm 19 and to a fixed point on the frame below the said arm so that it tends constantly to retract the bolt 18 and to swing the roller 21 upwardly. When the tray is rotating, the roller 21 bears against the flat uninterrupted surface of the tray and is, consequently, depressed against the tension of the spring 23 so that the bolt 18 is projected into the path of the door 16 and prevents opening movement of the door. When the rotation of the tray brings a recess 22 over the roller 21, the spring at once swings the roller into the said recess and the tray is then stopped but if the compartment thus brought under the hood 14 does not contain the particular merchandise desired by the purchaser, the rotation of the tray may be continued until the proper merchandise has been brought into the delivery position. As long as turning force is applied to the knob 12, the tray will be rotated inasmuch as no great amount of force will be required to overcome the seating of the roller 21 in the notch 22, but if the rotation of the shaft 11 be stopped with the roller engaging a seat or recess 22, the tray will be held stationary and the bolt 18 will remain in its retracted position so that the door 16 may be opened.

When the bolt 18 is retracted as just described, it removes one obstacle to the opening movement of the door but the door cannot be opened until coins have been inserted inasmuch as the coin chutes 24 and 25 project into the path of the door, these tubes being pivotally mounted, as at 26, upon the front wall of the cabinet and yieldably held with their lower ends in the path of the door by a spring 27 disposed between the upper extremity of the chute 25 and the adjacent portion of the front wall of the cabinet. Formed in the wall of the cabinet at the side of the door opening 15 and in such position that they register with the lower ends of the respective coin chutes 24, 25, are coin tubes 28, 29 which open at their lower ends into a money compartment 30 in which may be disposed a coin box or drawer 31. Within the cabinet and mounted upon a portion of the bracket or frame 20 are a pair of pivoted dogs 32, 33 which project forwardly into the respective coin tubes 28, 29 and serve as stops to arrest the descent of coins inserted through the respective coin chutes. The dogs 32 and 33 not only extend into different coin tubes but are also disposed at different elevations, as will be understood upon reference to Fig. 4, and the

exact position of these dogs may be determined by the coins which it is intended to require for the operation of the machine. In the present instance, the tube 29 requires the admission of two nickels, indicated at 34, 70 while the tube 28 is intended to receive a cent, as indicated at 35. The dogs 32 and 33 are held in their operative position by bolts 36 and 37, respectively, which are disposed vertically and slidable in guides 38 provided therefor in the internal supporting frame or bracket 20. The upper ends of these bolts 36, 37 are beveled, as shown at 39, and they project into the path of the door 16, as will be understood, the length and position of the bolts being such that normally a straight side or edge will be presented to the door and, consequently, the movement of the door will be prevented by contact with the said edge. It will also be noted upon reference to Fig. 4 that, when the coins are arrested by the dogs 32, 33, they will project above the upper ends of the respective coin tubes into the lower ends of the coin chutes so that the coin chutes will continue to block 90 the movement of the door and prevent access to the interior of the casing through the opening 40 which is provided to accommodate the coin chutes and permit the opening of the door. The coin chutes are swung outwardly by the action of the door 16 and in order that they may move over and away from the coins, they are provided in their inner walls at their lower extremities with notches 41 whereby they will clear the coins as they swing outwardly. To effect this outward movement of the coin chutes, a cam 42 is provided on the door and projects therefrom in position to ride against the side and inner wall of the chutes and thereby force the same outward against the strength of the spring 27 in an obvious manner. If coins have been inserted in the machine as required, the opening movement of the door will cause a projection 43 thereon at the lower edge of the same to ride upon the projecting coin and press the same downward within the respective coin tube so that the bolt 36 or 37 disposed at the back of said tube will be depressed, it being noted that the dogs 32, 33 pass through and seat in notches in the respective bolts so that downward pressure upon the coins tending to swing the dogs downward will transmit movement to the respective bolts and impart thereto a sufficient depression to bring the beveled edge 39 of the same into the path of the door, whereupon the continued movement of the door will cause it to ride on the bolt and depress it to the limit of its movement. Access to the compartment within the hood 14 cannot be had until the door is fully opened and the depression of the first bolt 37 will not permit the door to be fully opened inasmuch as it must still clear and operate 130

the second bolt 36 so that the mechanism cannot be actuated until the proper coins have been deposited. On the inner side of each bolt is a lug 44 which bears upon a 6 rocking arm 45 fulcrumed upon the inner supporting frame 20 and having its free end connected to a link 46 which depends to and is pivotally attached to a rocking arm or lever 47 also fulcrumed upon the inner supporting frame 20 and extending inwardly therefrom. The inner end of this arm 47 carries a bolt or locking pin 48 which is guided by an eye 49 at the inner end of an arm 50 forming a part of the frame or bracket 20. This bolt or locking pin 48 is normally held in its lowered position by a spring 51 attached to its lower end and to a fixed part of the cabinet and has its upper end arranged to engage in one of a series of 10 sockets 52 provided in the bottom of the tray 3. When this bolt 48 engages a socket 52, the tray will be held against further movement and it will be now understood that the bolts 36, 37 are so located that, when the 15 door 16 is opened to permit withdrawal of the article or package within the hood 14, both bolts will be held in their lowered position and the bolt 48 will, consequently, be held in engagement with the tray and the 20 tray cannot be moved to bring another article or package opposite the door opening until the door has been again closed and the mechanism thereby reset for the insertion of additional coins. When the door is returned 25 to closed position, the spring 51 withdraws the bolt 48 from the tray and projects the bolts 36, 37 into their upper positions so that the door cannot be again opened until 30 coins have been inserted. To facilitate the movement of the door 16, it is provided with a knob 53.

It is thought the operation will be fully understood from the foregoing description, taken in connection with the accompanying 45 drawings. After the tray has been set by manipulation of the knob 12 and the coins have been inserted, the door is pushed toward the opening position and the cam 42 thereon will ride against the coin chutes and 50 swing them outwardly, the continued movement of the door bringing the lower edge thereof and the presser 43 onto the upper projecting edge portion of the respective coins so that they will be depressed and an 55 initial lowering movement imparted to the bolts 36, 37 sufficient to bring the beveled edges thereof into position to be engaged by the corner of the door, whereupon the continued movement of the door will depress 60 said bolts and the lowering movement of the bolts will be transmitted through the rocking arm 45 and its connections to the bolt 48 so that the tray will be locked against movement. The door will, of course, extend 65 across the upper ends of the bolts and will

maintain the locked position of the tray until the door has been moved toward the closed position and, in order to clear the bolts, the door must be moved until it is nearly closed. If it be not fully closed, the cam 42 will prevent the return of the coin chutes to their inner operative position and the bolts will project upward into the path of the door so that the door cannot be again moved into open position and access to the hood 14 will be, 70 consequently, prevented. When the tray is moved so as to bring a second compartment into the discharge position, the roller 21 will be depressed and, consequently, an upward movement will be imparted to the bolt 18 so that, if the door be not fully closed, the upward movement of this bolt will be prevented and, therefore, further movement of the tray cannot be had. When the bolts 36, 37 are depressed by the door, the dogs or 75 coin rests 32, 33, are swung downwardly and inwardly out of the paths of the coins which then drop into the coin box.

It will be readily noted that I have provided a simple and compact mechanism 80 whereby merchandise may be vended automatically or without the services of a salesman, and the parts are of such construction and arrangement that they are not apt to get out of order. A great variety of merchandise may be dispensed through the use 85 of my machine and the articles may be changed from time to time as may be deemed desirable. The size of the coin tubes and coin chutes and the relative arrangement of 90 the mechanism directly operated by the coins may be varied as may be necessary to adapt the machine to merchandise of any particular value.

In order that the tray 3 may be held firmly to the pinion 10 and the roller 21, a presser roller 60 is preferably mounted upon the bracket or inner supporting frame 20 to ride upon the upper surface of the tray and thereby prevent the forward portion of the 110 same tilting or rocking in such a manner as will interfere with the successful operation of the mechanism.

Having thus described the invention, I claim:

1. In a vending machine, the combination of a casing, a tray movably mounted in the casing, a door mounted in the casing and controlling access to the tray, a bolt mounted in the path of the door, and coin-controlled means whereby opening movement of the door will retract said bolt and positively lock the tray against movement.

2. In a vending machine, the combination of a casing, a tray rotatably mounted therein, a door controlling access to the tray, bolts projecting into the path of the door, coin-controlled means whereby movement of the door will retract said bolts, and a bolt operatively connected with the first-mentioned

bolts whereby to lock the tray against movement when the first-mentioned bolts are retracted.

3. In a vending machine, the combination of a casing, a tray rotatably mounted therein, a door controlling access to the tray, bolts disposed in the path of the door, a rocking arm to be actuated by said bolts, a bolt disposed below the tray, operative connections between said bolt and the rocking arm, yieldable means holding the last-mentioned bolt out of engagement with the tray, and coin-controlled means whereby upon opening movement of the door the first-mentioned bolts will be retracted and the bolt below the tray will be moved into engagement therewith to lock the tray against movement.

4. In a vending machine, the combination of a casing, a door controlling access to the casing, bolts mounted on the casing and normally projecting into the path of the door, coin tubes in the casing adjacent the respective bolts, and coin rests extending across the coin tubes and engaged with said bolts, the said rests being so disposed as to support coins in the path of the door whereby opening movement of the door will depress the coins to impart movement to the bolts and then depress the bolts to com-

pletely retract the same and discharge the coins.

5. In a vending machine, the combination of a casing, a door controlling access to the casing, coin tubes in the casing arranged below the path of movement of the door, means for supporting coins in said tubes in the path of the door, bolts adjacent the coin tubes normally projecting into the path of the door and engaged with the coin-supporting means, coin chutes mounted pivotally on the casing and yieldably held in alignment with the coin tubes, and means on the door to move the coin chutes outwardly upon opening movement of the door.

6. In a vending machine, the combination of a casing having an opening in one wall, a tray movably mounted in the casing and having a plurality of compartments selectively presentable at the opening to cover the compartment of the tray presented to the opening, means for presenting a selected compartment to the opening, a door normally closing the opening, and coin-controlled means to permit opening of the door and prevent movement of the tray when the door is open.

In testimony whereof I affix my signature.

ROBERT KESSLER. [L. S.]

bolts whereby to lock the tray against movement when the first-mentioned bolts are retracted.

3. In a vending machine, the combination of a casing, a tray rotatably mounted therein, a door controlling access to the tray, bolts disposed in the path of the door, a rocking arm to be actuated by said bolts, a bolt disposed below the tray, operative connections between said bolt and the rocking arm, yieldable means holding the last-mentioned bolt out of engagement with the tray, and coin-controlled means whereby upon opening movement of the door the first-mentioned bolts will be retracted and the bolt below the tray will be moved into engagement therewith to lock the tray against movement.

4. In a vending machine, the combination of a casing, a door controlling access to the casing, bolts mounted on the casing and normally projecting into the path of the door, coin tubes in the casing adjacent the respective bolts, and coin rests extending across the coin tubes and engaged with said bolts, the said rests being so disposed as to support coins in the path of the door whereby opening movement of the door will depress the coins to impart movement to the bolts and then depress the bolts to com-

pletely retract the same and discharge the 30 coins.

5. In a vending machine, the combination of a casing, a door controlling access to the casing, coin tubes in the casing arranged below the path of movement of the door, means 35 for supporting coins in said tubes in the path of the door, bolts adjacent the coin tubes normally projecting into the path of the door and engaged with the coin-supporting means, coin chutes mounted pivotally on the casing and yieldably held in alinement with the coin tubes, and means on the door to move the coin chutes outwardly upon opening movement of the door.

6. In a vending machine, the combination 45 of a casing having an opening in one wall, a tray movably mounted in the casing and having a plurality of compartments selectively presentable at the opening to cover the compartment of the tray presented to the opening, means for presenting a selected compartment to the opening, a door normally closing the opening, and coin-controlled means to permit opening of the door and prevent movement of the tray when the 50 door is open.

In testimony whereof I affix my signature.
